US00D961579S

(12) **United States Design Patent** (10) **Patent No.:** **US D961,579 S**
(45) **Date of Patent:** **** Aug. 23, 2022**

(54) **COMPUTER WITH PITCHED FRONT BEZEL**

(71) Applicant: **Hewlett-Packard Development Company, L.P.**, Spring, TX (US)

(72) Inventors: **Joshua Glenn Little**, Mountain View, CA (US); **Jonathan Gomez Garcia**, San Francisco, CA (US)

(73) Assignee: **Hewlett-Packard Development Company, L.P.**, Spring, TX (US)

(**) Term: **15 Years**

(21) Appl. No.: **29/706,566**

(22) Filed: **Sep. 20, 2019**

(51) **LOC (13) Cl.** **14-02**

(52) **U.S. Cl.**

USPC **D14/308**

(58) **Field of Classification Search**

USPC D14/140.1, 140.2, 240, 242, 301–302, D14/308, 348–349, 351–359, 440–441, D14/444–446, 140.3, 219, 311–312, D14/353–355, 441–442, 450; D9/424, D9/430, 432–433; 206/706–709, 206/722–725; D13/103, 110–112, 122, D13/158–160, 184; D23/364–365, 270, D23/193, 209, 224, 257, 327, 365–366, D23/388, 392, 449–450; 361/679.01, 361/679.02, 679.21

CPC .. G06F 1/18; G06F 1/181; G06F 1/20; H05K 5/00; H05K 5/03; H05K 5/04; H05K 5/0213

(57) **CLAIM**

The ornamental design for a computer with pitched front bezel, as shown and described.

DESCRIPTION

FIG. 1 is a front, right, top perspective view of the claimed design;

FIG. 2 is a front, left, top perspective view thereof;

FIG. 3 is a front, right, bottom perspective view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a left-side elevational view thereof; and,

FIG. 9 is a right-side elevational view thereof.

The broken lines, shown in the drawings, represent portions of the computer with pitched front bezel and form no part of the claimed design.

1 Claim, 7 Drawing Sheets
